UNITED STATES PATENT OFFICE

LOTHAR R. ZIFFERER, OF COLUMBIA, PENNSYLVANIA

EXPANSION BOLT

Application filed June 15, 1928. Serial No. 285,734.

This invention relates to an expansion bolt having a shield with two pivoted sections between which is an expander in the form of a wedge nut.

5 The present improvements are directed to means which retains the expander assembled with the shield prior to expansion; which promotes an expansion of the shield prior to securing of the work in place; and which protects the expander prior to advance thereinto of the bolt which serves to draw the wedge nut longitudinally of the shield.

An exemplification of my invention is set forth in the accompanying drawing in the 15 manner following:

Figure 1 is a view in elevation of the shield as it appears when first introduced into the hole prepared for its reception in a body of masonry, concrete, or the like;

20 Fig. 2 is a similar view showing the shield advanced longitudinally to final position within the hole, the shield being initially expanded during this movement;

Fig. 3 is a similar view of the shield sections as they appear when further expanded upon application of the work engaging bolt to the expander;

30 Fig. 4 is a longitudinal section through the shield with the parts positioned about as shown in Fig. 3;

Fig. 5 is a longitudinal section taken on line 5—5 of Fig. 4;

Fig. 6 is a view in perspective of the expander per se; and

35 Fig. 7 is a view in perspective of the clip forming the expander retaining means.

In a body A of concrete, masonry, or the like, a hole B is provided for the reception of the present expansion bolt which comprises 40 a pair of shield sections C and C' substantially alike. One of these sections may be equipped with a pair of lugs 8 which overlaps the other section, whereon are provided laterally extending pins 9 extending through apertures 45 in the lugs whereby to establish a pivotal connection between the two sections of the shield. This connection, it will be noted, is near the outer shield end so as to permit the inner ends of the shield sections to swing apart freely 50 a limited distance in response to forces of

expansion produced by advance of a wedge nut D. This free swinging movement is arrested when the outer ends of the shield sections come together, as shown in Fig. 2. The outer surfaces of the two shield sections may be provided with ribs 10 and 11 disposed circumferentially and longitudinally so as to resist longitudinal and rotary movements of the expansion when the shield sections are engaged with the wall surfaces surrounding 55 the hole B.

The interior of each shield section is provided with a concave inclined surface 12 against which the expander exerts an increasing pressure as it is advanced toward the 60 outer end of the expansion. The expander, as best shown in Fig. 6, is in the general form of a truncated cone having an elliptical cross section whereby to provide tapering sides 13 adapted to engage with the inclined surfaces 12 upon the interior of the shield sections. For the major portion of its length the 65 expander is split by the provision of shouldered 70 slots 14 which are arranged oppositely in the plane of its shorter axis. Each of these slots 75 proceeds from its inner larger end close to the outer smaller end, and may terminate in an enlargement 50 of such character as to facilitate bending of the two split nut sections in response to a sufficient force which 80 is developed for this purpose. The outer 85 smaller end of the nut is continuous so as to have the form of a collar 16. The nut is threaded interiorly at 17 to cooperate with the screw threads of a bolt E adapted to pass 90 through the work F so as to present the bolt head 18 in engagement therewith. The threaded hole which is extended lengthwise of the nut is preferably tapered slightly toward its inner end so as to offer an increasing 95 resistance to the passage therethrough of the threaded bolt.

The meeting edges of the shield sections near their inner ends are cut away at 19 to provide spaces 20 closed at its bottom by the projection of two pairs of lugs 21 which extend from the shield sections as shown. Disposed within these spaces and supported upon the two pairs of projecting lugs are 100 flanges 22 which are outturned from two ver-

tical arms 23 of a clip G (see Fig. 7) having a bottom plate 24. During handling of the expansion, and prior to operation thereof, this clip is disposed as shown in Fig. 1 with its bottom plate 24 underlying the expander to retain the same assembled between the shield sections. The clip arms are initially disposed with the slots 14 of the split expander, and close to the shouldered portions of such slots so as to be correctly positioned relative thereto as shown in Fig. 5. The clip which is bendable may be easily applied to or removed from the shield, as occasion may require.

15 The present expansion shield is adapted to be anchored in a hole having a depth slightly in excess of its own length. The expander and retaining clip therefor are initially protruded beyond the inner end of the shield, as shown in Fig. 1, thereby causing the outer shield end to protrude from the hole for a slight distance. By a blow from a hammer or other implement, the shield may be driven into the hole to the final longitudinal position which is indicated in Fig. 2.

20 In this operation, the expander and clip are forced further into the shield whereby to produce an initial expansion of its two sections, but the condition of the expander itself remains unchanged due to the interposition of the clip arms which prevent the split sections of the nut from being forced toward one another. While in this position, the shield will remain stationary during application of the bolt E which passes through the work and into the expander preliminary to further separation of the shield sections. It is to be noted that up to this point the clip bottom 24 remains tight against the

25 lower end of the expander so as to prevent the entrance thereinto of any dirt or grit which otherwise might foul the nut threads and interfere with subsequent operations.

30 The bolt is adapted to enter freely into the continuous upper end of the expander which remains undistorted, as above noted. As the bolt is screwed further into the expander, it encounters an increasing friction owing to the slight taper of the threaded split sections of the nut. Eventually the clip arms will be crushed or crowded away from between the split sections of the expander in response to an increase in the wedge force developed. By the application of a sufficient

35 torsional force the bolt will be required to pass through the expander as far as necessary, thereby drawing the same outwardly when the bolt head 18 engages with the work. The final position of the expander may be well toward the outer end of the shield sections, depending upon the degree of expansion which is required for producing a secure anchorage.

40 The present expansion bolt is advantageous on account of the several features al-

ready referred to. It is also capable of expansion to an unusual degree. The pivoted outer end of the expansion is unaffected to any considerable extent by the separation of the two shields, due to the spreading movement thereof being confined mostly to the inner end of the device. In case it becomes necessary to withdraw the bolt for removal of the work, the split sections of the nut will continue to remain tightly wedged against the tapering interior surfaces of the shield so as to prevent collapse of its sections, thereby preserving the parts in condition for further service when the bolt is reintroduced. Also, because of the friction obtaining between the bolt and the expander, the former will not tend to unscrew should the work become loose for any reason. This is of particular advantage where the expansion is used to fasten a seat to the floor, it being a common fault that once the seat starts to work loose, the bolt will also tend to loosen its hold on the expander until finally it disengages completely therefrom.

45 I claim:

1. An expansion bolt comprising a pair of shield sections pivoted at their outer ends and provided interiorly with surfaces which taper inwardly from the inner end and the adjacent edges of which are cut away to provide a retaining slot, a tapered expander nut movable between the shield sections toward the outer end thereof to produce expansion, and a clip of less length than the shield sections movably retained within the slot and overlying the corresponding end of the nut to retain the same between the shield sections, substantially as described.

50 2. An expansion bolt comprising a pair of separable shield sections having inclined surfaces interiorly thereof and cut away portions adjacent the inner ends, a wedge-shaped expander movable between the sections toward the outer end thereof for producing expansion, and a clip of less length than the shield sections having means movably retained by the cut away portion of the shield sections and a bottom plate disposed normally beyond the inner end of the shield sections to furnish support for the expander, whereby the latter is retained between the shield sections with the inner end of the expander protruded past the inner end of the shield, substantially as described.

55 3. An expansion bolt comprising a pair of separable shield sections having adjacent their inner ends opposite pairs of lugs which co-operate to provide two supports, a sheet metal clip in the form of a plate with upturned parallel arms each having an out-turned end adapted to rest on one of the supports, the length of the clip being less than that of the shield sections and a wedge-shaped expander entered partly between the shield sections and retained against displace-

ment therefrom by engagement with the plate end of the clip, substantially as described.

4. An expansion bolt comprising a pair of separable shield sections, means connecting the shield sections for pivotal movement adjacent their outer ends and adapted to impose a normal limit on such swinging movement, a clip having a pair of arms receivable between the shield sections at their inner ends, a pair of lugs projecting from each shield section toward the other adapted to engage with said arms to retain the clip in place, the extent of normal swinging of the shield sections being insufficient to permit demounting of the clip from the shield, and an expander in the form of a wedge retained by the clip and movable between the shield sections for separating the same, substantially as described.
- 10 5. An expansion bolt comprising two pivotally joined shield sections formed at their inner ends with cooperating projections providing a stop, an expander initially disposed in part to the outside of the inner shield end and movable between the sections thereof to swing one relative to the other, and a clip of less length than the shield sections underlying the expander outside of the inner shield and movable between said shield sections having 25 retaining means adapted to engage the stop at the inner shield end, substantially as described.
- 30 6. An expansion bolt comprising a split shield formed interiorly with tapered surfaces, a split expander movable between the shield sections for producing separation thereof, and means connecting the expander to the shield and extending into the split of the expander to prevent distortion of the former during initial expansion of the latter.

In testimony whereof I have hereunto set my hand this 7th day of June, 1928.
